United States Patent Office

Des. 222,917
Patented Feb. 1, 1972

222,917

MODEL RACING CAR

Eric Harrison Broadley, Pangborne, near Reading, England, assignor to Lola Cars Limited, Slough, England

Filed Sept. 18, 1970, Ser. No. 25,062

Claims priority, application Great Britain Mar. 23, 1970; May 20, 1970

Term of patent 7 years

Int. Cl. D21—01

U.S. Cl. D34—15

FIG. 1 is a top plan view of the model racing car showing my new design;

FIG. 2 is a front elevational view thereof,

FIG. 3 is a left side elevational view, the right side being substantially a mirror image thereof; and

FIG. 4 is a rear elevational view thereof.

I claim:

The ornamental design for a model racing car, as shown and described.
